UNITED STATES PATENT OFFICE

160,184

RADIATOR GRILL FOR AUTOMOBILES

Garfield P. Lennartz, Chicago, Ill.

Application May 2, 1949, Serial No. 2,380

Term of patent 7 years

(Cl. D14—18)

To all whom it may concern:

Be it known that I, Garfield P. Lennartz, a citizen of the United States, residing at Chicago, in the county of Cook and State of Illinois, have invented a new, original, and ornamental Design for a Radiator Grill for Automobiles, of which the following is a specification, reference being had to the accompanying drawing, forming a part thereof.

Fig. 1 is a front view of a radiator grill for automobiles embodying my new design;

Fig. 2 is a top view of Fig. 1; and

Fig. 3 is a side view thereof.

I claim:

The ornamental design for a radiator grill for automobiles, substantially as shown.

GARFIELD P. LENNARTZ.
